(57) **CLAIM**

The ornamental design for a fluid container with cap and cup, as shown and described.

DESCRIPTION

FIG. 1 is a front isometric view of an ornamental design for a fluid container with cap and cup showing the new design. FIG. 2 is an exploded view thereof, showing the fluid container with an included cap member and an included cup member, with the cap member and the cup member exploded away.

FIG. 3 is a front elevational view of the fluid container with cap and cup of FIG. 1; the rear elevational view being a mirror image thereof;

FIG. 4 is a top plan view thereof.

FIG. 5 is a bottom plan view thereof.

FIG. 6 is a front isometric view of the fluid container, omitting the cap member and the cup member.

FIG. 7 is a top plan view thereof.

FIG. 8 is a front elevational view thereof.

FIG. 9 is a back elevational view thereof.

FIG. 10 is a front isometric view of the cap member, omitting the fluid container and the cup member.

FIG. 11 is a top plan view thereof.

FIG. 12 is a front elevational view thereof.

FIG. 13 is a bottom plan view thereof.

FIG. 14 is a back elevational view thereof, with the cap member depicted upside down.

FIG. 15 is a front isometric view of the cup member, omitting the fluid container and the cap member.

FIG. 16 is a cross section view of the cup member of FIG. 15 taken along line 16-16 of FIG. 17.

FIG. 17 is a bottom plan view of the cup member of FIG. 15; and,

FIG. 18 is a cross section view of the cup member of FIG. 15 taken along line 18-18 of FIG. 17.

1 Claim, 7 Drawing Sheets
